SELF-PROPELLED PROJECTILE FOR
DISTRIBUTING MATERIAL

Morris R. Jeppson, United States Army

Application October 27, 1944, Serial No. 560,579

3 Claims. (Cl. 102—34.4)

(Granted under the act of March 3, 1883, as
amended April 30, 1928; 370 O. G. 757)**1**

The invention described herein may be manufactured and used by or for the Government for governmental purposes, without the payment to me of any royalty thereon.

This invention relates generally to methods and devices for distributing material, and specifically to a projectile for automatically releasing and distributing material at intervals during the travel of the projectile.

Certain military operations require the release or distribution of quantities of material of various types over selected portions of enemy territory. This material must be distributed and released in the air in such manner that it will float slowly to the earth. Heretofore, such operations were usually carried out by merely dumping the material in batches at successive intervals or all at once from an airplane flying over enemy-held territory. This procedure has been found undesirable for a number of reasons, the main objection being that the airplane must necessarily expose itself to anti-aircraft fire, which is bound to be intense over the areas upon which the material must be distributed.

It is an object of my invention to provide a device which will automatically release quantities of material in the air at desired intervals.

It is another object of my invention to provide a method for automatically releasing quantities of material at desired intervals in the air.

Other objectives and advantages will become apparent as the following description is read in connection with the accompanying drawing in which is illustrated a side view partly in section of one embodiment of my invention. It is to be understood, however, that this embodiment merely serves as an illustration of the underlying principles of the invention so that they may be readily comprehended by those skilled in the art and is not intended as limiting the invention to the specific form disclosed therein.

In general, my invention may comprise a self-propelled projectile such as a rocket, to which is rigidly attached a receptacle which contains a series of bundles, batches, stacks, or piles of the material which it is desired to distribute. These bundles or batches of material are arranged serially and each batch or bundle is separated from the other by a small expelling charge. Means is provided to successively fire each expelling charge after the projectile has traveled a certain portion of its trajectory, so that as the projectile continues on its way there will be released and projected rearwardly at desired in-

2

tervals a batch or bundle of the material it is desired to distribute.

In the drawing, the reference numeral 10 refers to a self-propelled projectile of the rocket type having guide fins or vanes 11 and a propellant charge 12. A receptacle or container 14 is rigidly supported from the projectile body 10 by means of the struts or braces 13. Within the container 14 is placed a series of bundles, batches, stacks, or piles of the material 15 which it is desired to distribute. Each bundle or batch of material is separated from the other by a quantity of expelling charge 16. A fuse 17 has an end 19 situated within the propellant charge 12 of the rocket 10 so that the fuse will be ignited after a certain amount of rocket propellant charge has been burned. The fuse 17 is led down through one of the struts or braces 13 into the upper portion of the container 14 so that contact is made with each expelling charge 16, situated between each batch or bundle of material within the container 14. After the container 14 has been loaded it is closed by means of a plug 18. The plug 18 may be fitted into the end of the container 14 in a manner similar to the wadding in a shot-gun shell.

In operation, the rocket 10 will be launched either from an aircraft in flight or from a stationary or moving platform on the ground. After the projectile has been in flight a certain length of time the end 19 of the fuse 17 will become ignited. The time at which this occurs depends upon the rate at which the propellant 12 burns, and also the position the end 19 of the fuse 17 has with respect to the longitudinal dimensions of the propellant charge 12. When the burning fuse 17 reaches the first expelling charge 16 in the container 14 the batch or bundle of material 15 will be blown rearwardly out of the container 14. A period of time will ensue until the burning fuse reaches the next expelling charge, at which time the next bundle or batch of material will be expelled rearwardly out of the container into the air to float slowly to the earth below. This series of events will occur until all of the bundles or batches of material have been pushed out of the container 14. The fuse 17 must be so proportioned that the last batch of material will leave the container 14 before the projectile has reached the end of its trajectory.

In the utilization of my method and device it is possible for the projectile to be launched from an airplane in flight in such manner that the carrying plane can elevate the trajectory of the projectile so that it will release the material at

an altitude above the ceiling of any airplane.

The material which may be distributed by my device and method may be for example, propaganda leaflets, incendiary cards, powdered substances, or any other material that is capable of being distributed from the air. The aforementioned are purely illustrative and are not intended to limit the scope of my invention.

Having thus described my invention, what is claimed is:

1. A device for distributing material, comprising a self-propelled projectile, a container supported by said projectile, a series of separated stacks of material positioned within said container, expelling means separating each of said stacks of material, and means to actuate said expelling means in a successive order.

2. A device for distributing material, comprising a projectile, means within said projectile for causing its propulsion, a container attached to said projectile, a series of separated piles of material positioned within said container, expelling means, separating each of said piles of material, and a fuse leading from said first named propulsion means to said expelling means.

3. A device for distributing material, comprising

ing a projectile, means within said projectile for causing its propulsion, a container rigidly supported from said projectile, a series of stacks of material serially arranged within said container, each of said stacks being longitudinally separated by a transversely positioned expelling charge, a fuse leading from said propulsion means to each of said expelling charges, and means to automatically ignite said fuse a predetermined period of time after initiation of flight of said projectile.
